PROCESS FOR CONVERTING HYDRO-CARBONS

Carbon P. Dubbs, Wilmette, Ill., assignor, by
mesne assignments, to Universal Oil Products
Company, Chicago, Ill., a corporation of Dela-
ware

Application June 20, 1918, Serial No. 240,913

13 Claims. (Cl. 196—48)

This invention relates to improvements in process for converting hydrocarbons and refers more particularly to a process of converting heavy into lighter hydrocarbons such as gasoline like products.

5 Among the salient objects of the invention are to provide a process in which the oil is compelled to pass in a plurality of relatively small streams through the fire or cracking zone and then 10 through a larger chamber or chambers located outside of the fire zone and forming the vapor or distilling zone; to provide a process in which the oil is circulated rapidly through the fire zone and relatively slowly through the vaporizing zone; 15 to provide a process in which the oil is circulated through the fire zone in streams of progressively decreasing size to insure the highest economy of operation and most efficient cracking; to provide a process which permits of the use of relatively small pipes in the fire zone and in which the 20 deposition of carbon is substantially eliminated in that part of the apparatus which is subjected to the highest heat; to provide a process in which the speed of circulation of the oil can be regulated and in which the speed of the oil may be 25 varied as desired; to provide a process in which the precipitated carbon is deposited in that part of the apparatus located outside of the fire zone; to provide a process in which a regulated quantity of oil is at all times automatically supplied 30 to the system to prevent the pipes becoming dry; to provide a process in which the cracking, distilling and condensing can take place under the pressure of the generated vapors.

35 In the drawings:

Fig. 1 is a side elevation of the apparatus with parts shown in dotted lines.

Fig. 2 is a view partly in plan and partly in horizontal section.

40 Fig. 3 is a transverse cross-sectional view.

Fig. 4 is a detailed view showing the aerial condenser and water condenser. Suitable legends and arrows are applied upon the face of the drawings, the arrows showing the direction of flow 45 of the oil.

50 Referring to the drawings, 1 designates the furnace, in the fire zone of which are mounted a plurality of sets of relatively small pipes, 2, 3, 4 and 5 respectively. The first set, 2, may be of 55 1 1/4 inches in diameter, the set 3 an inch in diameter, the set 4 three fourths inch in diameter and the set 5 one half inch in diameter. The exact diameter of each set may of course vary with conditions of operation but should be of the correct size relative to the desired speed, friction,

amount of vapors taken off, character of product desired, etc.

I have found in practice that the decrease in diameter is advantageous, but just what chemical changes take place different from having pipe of the same diameter I am unable to state.

These pipes are connected in series and each set is provided with a pump 6, the connections from the coils to the pumps being controlled by suitable valves. The pump for the largest size

10 pipe or coil is connected to a suitable source of bulk supply. Mounted above the cracking coils and located outside of the fire zone are four vapor chambers, 7, 8, 9, and 10 respectively, there being a vapor chamber for each of the cracking coils.

15 These vapor chambers may take the form of ten inch pipes and are inclined somewhat downwardly toward the end of the apparatus at which the pumps are located. The vapor chambers are connected at one end to the respective coils by pipes

11 and at their other ends to the corresponding pump by pipes 12. A vertical aerial condenser 13 having a suitable connection controlled by a valve 14 is disposed in communication with each

20 of said vapor chambers. The aerials are connected to the inclined pipes 15 leading to manifold 16 which in turn is connected by pipe 17 to the water condenser coil 18. The condenser 18 leads to receiving tank 19 having draw-off 20

25 which is controlled by valve 21. Valves 22 are interposed in the reflux pipes 15 so that pressure can be regulated on the system as desired and a reflux cut out of the system if desired. A

30 baffle 23 to restrict the passage of the vapors may be interposed, if desired, in the vapor chambers which are also provided with gauges 24 and 25.

The small pipes are at all times filled with oil but of course the vapor chambers will not be. To prevent the system going dry by excess vaporization or otherwise, I provide means for automatically supplying the oil to the system.

To this end, I provide a tank 26 containing oil and connected by pipe 27 to the pump 6, a valve 28 being interposed in the pipe 27. The oil in this

35 tank is provided with a float valve 29 the arrangements being such that as the oil in the vapor chambers gets below a certain level that the oil in the tank will automatically be delivered to the pump. The oil is supplied to tank 26 from pipe

29' from any suitable source of supply. As the

40 vapor chambers freely communicate with the tank 26 through lines 12, vertical connecting pipes 28^a, header 28^b and draw-off line 27, the

45 level in the tank and vapor chambers is substantially the same when the valves in the line 12

5

55

and 27 are open. Connecting pipes from the bottom of the vertical lines 28^a to the inlet side of the respective pumps 6 direct the oil from the tank 26 to be introduced to the system, thereby 5 keeping the oil level in the tank and vapor chambers substantially the same. A balancing pressure of cold incondensable gas is maintained above the level of the oil by connecting the tank to the gas outlet 30 of the receiving tank.

10 The temperature and pressure to which the oil is subjected will vary with conditions, both with the character of the oil treated and with the desired gravity or end point to be obtained as well as other conditions. The pressure may vary 15 from 50 to several hundred pounds although in some cases the process may be operated at less than 50 pounds pressure, as for example 20 to 30 pounds. The temperature of the oil in the small tubes will vary from about 400° F., more or 20 less, to 1200° F., more or less.

It is impossible to give any specifically definite pressures and temperatures, as they vary with different oils, as will also the yield of gasoline. In addition, the yield of gasoline will vary, 25 depending on what gravity and end point is desired. The fixed gases generated are led out of the system. The percentage of gasoline produced may vary from 20 to 50 per cent, or more, of the original crude material used.

30 The residue is drawn out of the last vapor chamber through pipe 31 which is connected by pipe 32 to a fractionating still 33. This still 33 which operates at atmospheric pressure is connected with gooseneck 34, water condenser 35 and receiving tank 36. Distillates from tank 36 are delivered through any suitable pipe and pumped (not shown) to the inlets of the small coils in any convenient manner. The pipe 32 is provided with a valve 37 set at a pressure under which 40 the system is operated. In pipe 32 is interposed a tank 38. In this tank 38 is interposed a float valve 39 which regulates the rate of flow of the oil from the pressure sealing tank 38 by controlling the quantity of oil discharged through the 45 pipe 32, it being appreciated that this valve 39 is mounted at the inlet of said pipe 32 and serves to keep a level of oil in the tank above the pipe opening, allowing a constant quantity of oil to discharge to the fractionating still because of the 50 set position of the valve, and in cases where there is a sudden rise of oil in the last vapor chamber 10, this oil seeking its lowest level passes to the tank 38, raising the float valve therein and permitting an increased quantity of the residual oil 55 to flow out into the fractionating tank. The oil is maintained at the given level in the tank 38, so as to prevent the escape of pressure gases along with the discharging oil, it being apparent from Figure 4 that this level is always above the outlet 60 pipe 32, and the float valve merely functions to continuously allow a given stream of oil to discharge under normal operating conditions, and in cases of a sudden excess rise of the oil level, a greater quantity of oil is discharged by a further 65 raising of the float valve. The upper end of this chamber 38 is provided with a gas inlet pipe 40 which is adapted to receive the uncondensable gases from the receiving tank 19. The arrangement is such that when the level in the last vapor 70 chamber exceeds the amount which would promote the cracking reaction, the float valve will raise and whenever the pressure becomes sufficient to operate valve 37 permit the excess residue to pass into the fractionating still. The construction is similar to that shown in tank 26.

The residue which goes into the fractionating still is there fractionally distilled and the distillates which go over into the condenser are again returned to the cracking system for retreatment. The residue left in the cracking still will contain 5 most of the precipitated carbon.

Although the operating conditions on the different types of oil will vary through quite an extensive range, the conditions when operating on Mid-Continent gas oil are as follows:—By introducing gas oil of approximately 32° B. and heating the same to a temperature from approximately 700° to 900° F. while maintaining a pressure ranging from 50–200 pounds and by continuously circulating the oil and treating the residual oil from the vapor chambers as disclosed, I have been able to recover from 50 to 60% of the original oil charge in the form of distillate of approximately 51° B.

I claim as my invention:

1. A process of converting heavy into lighter hydrocarbons, which consists in causing the oil to pass in a relatively small stream through a cracking zone, and thence to a relatively large vapor chamber, passing the unvaporized oil from said vapor chamber through the cracking zone in a stream of decreased diameter relative to the first mentioned stream, in passing said oil and vapors from the last mentioned stream into a vapor chamber, in removing vapors therefrom, in passing the unvaporized oil from said vapor chamber in a stream of smaller diameter through the cracking zone and in thence introducing the same into a vapor chamber, in taking off vapors from said chamber, in maintaining a pressure above atmospheric in the system, in taking off the residue from the system and fractionally distilling it at substantially atmospheric pressure and returning the distillate obtained in said fractionation to the cracking zone for retreatment. 20

2. A process of converting heavy into lighter hydrocarbons, consisting in causing the oil to pass in a relatively small stream through a cracking zone and thence to a relatively large vapor chamber, in passing the unvaporized oil from said vapor chamber through the cracking zone in a stream of decreased diameter relative to said first mentioned stream, in then introducing the oil and vapors from said stream to a vapor chamber, in taking off vapors from said vapor chamber, and condensing and collecting them, in maintaining a pressure above atmospheric on the oil in the system, in taking off the residue from the system and fractionally distilling it at substantially atmospheric pressure, and returning the distillate obtained in said fractionation to the cracking zone for retreatment. 30

3. A process of converting heavy into lighter hydrocarbons, consisting in causing the oil to pass in a relatively small stream through a cracking zone and thence to a relatively large vapor chamber, passing the unvaporized oil from said vapor chamber through the cracking zone in a stream of decreased diameter relative to said first mentioned stream and thence into a relatively large vapor chamber, in taking off vapors from said vapor chambers, in maintaining a pressure above atmospheric on the oil in the system, and in automatically regulating the level of the oil in the system to prevent the tubes containing 40 the oil from becoming dry.

4. An improvement in the art of pressure distillation of petroleum oils for converting heavy into lighter hydrocarbons, which consists in continuously passing hydrocarbon oil in a small 45

stream through successive heating coils and vapor chambers where said oil is maintained under cracking conditions of temperature and pressure, in discharging the vapors from said vapor chambers, in withdrawing the residue produced from the cracking of the oil, and in releasing the pressure on said heated residue when introduced to a still, in heating the residue in said still while under substantially atmospheric pressure to discharge off the lighter fractions thereof, and in returning said distilled fractions for further cracking.

5. The herein described method of treating hydrocarbon oil which consists in subjecting a body of oil to heat and pressure, drawing off the heavier

10 oil from the first body of oil to form a second body of oil also maintained under pressure, and reducing the pressure on the second body of oil to effect the distillation of a portion of said oil.

15 6. The herein described method of treating hydrocarbon oil which consists in subjecting a body of oil to heat and pressure to release vapors from the oil, drawing off the heavier oil from the first body of oil and holding it under pressure, reducing the pressure on said heavier oil to effect the distillation of a portion of said oil, then cooling the distilled portion of the oil to liquefy the same, and then returning the resultant liquid to the main body of oil for retreatment.

20 7. The herein described method of treating hydrocarbon oils which consists in subjecting a body of oil to heat and pressure separately recovering released vapors from the oil, drawing off the heavier oil from said body of oil and holding it under pressure, and reducing the pressure on the heavier oil to effect a separation of its lighter constituents from its heavier constituents.

25 8. A conversion process which comprises subjecting a body of hydrocarbon oil to cracking conditions of temperature and superatmospheric pressure, removing unvaporized oil from said body and maintaining it in a second body under superatmospheric pressure, and reducing the pressure on said unvaporized oil to vaporize a substantial portion thereof.

30 9. A conversion process which comprises subjecting a body of hydrocarbon oil to cracking conditions of temperature and superatmospheric pressure in a cracking zone, separately removing vapors and unvaporized oil from said zone, main-

taining a body of the withdrawn unvaporized oil under superatmospheric pressure in a second zone, and subsequently reducing the pressure on the unvaporized oil to vaporize a substantial portion thereof.

5

10 10. A conversion process which comprises subjecting a body of hydrocarbon oil to cracking conditions of temperature and superatmospheric pressure, removing unvaporized oil from said body and maintaining it in a second body under superatmospheric pressure, reducing the pressure on said unvaporized oil to vaporize a substantial portion thereof and returning resultant vaporized portions to the process for retreatment under cracking conditions.

15

15 11. A conversion process which comprises subjecting a body of hydrocarbon oil to cracking conditions of temperature and superatmospheric pressure in a cracking zone, separately removing vapors and unvaporized oil from said zone, maintaining a body of the withdrawn unvaporized oil under superatmospheric pressure in a second zone, subsequently reducing the pressure on the unvaporized oil to vaporize a substantial portion thereof, condensing the vapors evolved by the pressure reduction and returning resultant condensate to the cracking zone.

20

20 12. In the conversion of hydrocarbon oils wherein the oil is heated to cracking temperature in a restricted heating zone and then introduced into an enlarged zone maintained under superatmospheric pressure, the improvement which comprises removing unvaporized oil from said enlarged zone and maintaining a body thereof under superatmospheric pressure, and subsequently 30 flash distilling the unvaporized oil by pressure reduction.

35

35 13. In the conversion of hydrocarbon oils wherein the oil is heated to cracking temperature in a restricted heating zone and then introduced into an enlarged zone maintained under superatmospheric pressure, the improvement which comprises removing unvaporized oils from said enlarged zone and maintaining a body thereof under superatmospheric pressure, subsequently 40 flash distilling the unvaporized oil by pressure reduction, and returning resultant flash distillate to the heating zone.
